[57] CLAIM

The ornamental design for a set of food preparation rollers, as shown and described.

DESCRIPTION

FIG. 1 is a top plan view of a first roller of the set of food preparation rollers, the respective side elevation views and bottom plan view thereof being identical;

FIG. 2 is an end elevation view of one end of the first roller;
FIG. 3 is an end elevation view of the other end of the first roller;

FIG. 4 is a perspective view of the first roller;

FIG. 5 is a top plan view of the second roller of the set of food preparation rollers, the respective side elevational views and bottom plan view thereof being identical;

FIG. 6 is an end elevational view of one end of the second roller;

FIG. 7 is an end elevational view of the other end of the second roller;

FIG. 8 is a perspective view of the second roller;

FIG. 9 is a first perspective view of the rollers of the set of food preparation rollers; and,

FIG. 10 is a second perspective view of the rollers of the set of food preparation rollers.
